(57) **CLAIM**

The ornamental design for a electric cooktop, as shown and described.

DESCRIPTION

FIG. 1 is a rear perspective view of an electric cooktop; FIG. 2 is a front perspective view an electric cooktop; FIG. 3 is a front elevational view of an electric cooktop; FIG. 4 is a back elevational view of an electric cooktop FIG. 5 is a left side elevational view of an electric cooktop FIG. 6 is a right side elevational view of an electric cooktop; FIG. 7 is a top elevational view of an electric cooktop; FIG. 8 is a bottom elevational view of an electric cooktop; FIG. 9 is a front perspective view of the electric cooktop installed on a front control oven;

FIG. 10 is a front perspective view of the electric cooktop installed in a rear control oven; and,

FIG. 11 is a partial side perspective view of the electric cooktop shown in FIG. 10.

The broken line showing of various features, including the oven, oven controls, flanges, fasteners, and heating elements, is for the purpose of illustrating unclaimed portions of the electric cooktop and forms no part of the claimed design.

The broken lines on the electric cooktop are also illustrative only and form no part of the claimed design.

1 Claim, 9 Drawing Sheets
